UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT MOLDS.

Application filed June 18, 1923. Serial No. 646,086.

To all whom it may concern:

Be it known that BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Feeders for Ingot Molds, of which the following is a specification.

Our invention relates to improvements in extensible feeders for ingot molds.

The object of our invention is to provide an extensible feeder for ingot molds having 15 all of the advantages of the solid or one-piece feeder to prevent seams and holes known as "piping" and also reduce segregation to a minimum.

Another object of our invention is to provide 20 an extensible feeder whereby the distance the feeder extends above the mold may be readily varied and whereby the length of the ingot can be made greater or less in the same size mold.

25 A further object of our invention is to provide an extensible feeder in which any number of sections can be placed upon each other to build the feeder up at the same time holding them against lateral movement 30 in proper alignment.

A still further object of our invention is to provide an extensible feeder for ingot molds in which the sections are made precisely alike and interchangeable and at the 35 same time provide a cheap and effective structure having certain details and combination of parts hereinafter more fully set forth.

In the accompanying drawings:—

40 Figure 1 is a perspective view of an ingot mold showing the feeder extended by three additional sections.

Figure 2 is a vertical transverse sectional view.

45 Figure 3 is a vertical sectional view partly in side elevation showing a modified form.

Figure 4 is a vertical sectional view of another modified form.

50 Figure 5 is a vertical sectional view of a still further modified form.

Figure 6 is a vertical sectional view showing pins and recesses for interlocking the sections together.

55 Figure 7 is a vertical sectional view showing the beveled contacting surfaces between

the sections for holding them against lateral movement.

Figure 8 is a sectional view similar to Figure 7 showing both the upper and lower ends of the sections beveled.

60 Figure 9 is a sectional view showing the sections beveled in the reverse direction to Figure 7.

Figure 10 is a vertical sectional view similar to Figure 8 showing the sections 65 beveled in the reverse direction.

Figure 11 is a vertical sectional view showing a stepped interlocking connection between the sections.

Figure 12 is a vertical sectional view 70 showing the sections having off-set annular flanges forming interlocking recesses.

Figure 13 is a vertical sectional view 75 showing the sections having semicircular grooves forming interlocking members.

Figure 14 is a vertical sectional view similar to Figure 13 showing the curves arranged in the opposite direction.

Figure 15 is a sectional view of a modified 80 form of interlocking means.

Figure 16 is a vertical sectional view in which the contacting edges of the sections are perfectly flat and held against lateral movement by a band.

85 Referring now to the drawings, 1 represents the ingot mold which is of the usual construction and needs no further description. Arranged within the upper end of the mold is the main body portion 2 of the feeder which has arranged on its outer periphery a number of ribs 3, which are adapted to engage the upper end of the mold and hold the feeder within the upper end of the mold. The upper edge of the main body portion 2 of the feeder at opposite 90 sides is provided with the upwardly extending lugs 4 and 5 having their inner faces beveled, as indicated at 6. The additional section 7 has its lower face provided with corresponding recesses 8 adapted to receive the lugs 4 and 5 of the body portion 2 and owing to the bevel thereof the section 7 will center itself upon the body portion with their inner faces flush. The upper edge of the section 7 is provided with lugs 9 and 10

95 constructed exactly the same as the lugs 4 and 5 carried by the body portion 2. The sections 11 and 12 are constructed exactly 100 like the section 7 and thus it will be seen that any number of these sections can be 105

110

placed one upon the other to build the feeder up to the proper height desired. In the form shown in Figure 3 the same reference numerals indicate like parts corresponding to Figure 2. A strengthening band 13 is arranged around the outside of the sections to prevent the pressure of the metal from breaking and separating the sections.

10 In Figure 4 the body portion 2 of the feeder is provided at its upper edge with the wedge-shaped annular rib 14 adapted to enter the corresponding recess 15 in the lower face of the section 16. The upper edge of the section 16 is provided with an annular rib 17 the same shape as the rib 14 and adapted to enter a recess in the section 18. While I have shown but two sections upon the main body portion, any desired number of sections can be placed thereon to extend the feeder.

In Figure 5 the main body portion 2 at proper intervals around its upper edge is provided with pins 19 adapted to enter recesses 20 in the section 21 and thus hold the section 21 against lateral movement on the main body portion. The upper edge of the section 21 is provided with a pin 22 adapted to enter the recess in the section 23. In Figure 5 the sections 21 and 23 are of different height so that the feeder can be built up to the desired height.

15 In Figure 6 the main body portion 2 of the feeder is provided at its upper edge with lugs 24 having the beveled faces 25 terminating in horizontal faces 26 which enter grooves 27 of corresponding shape in the lower edge of the section 28. The upper edge of the section 28 is provided with lugs 29 corresponding in shape with the lugs 24 and adapted to enter recesses in the section 30.

20 In Figure 7 the main body portion 2 has its upper edge beveled inwardly, as indicated at 31, and the section 32 has its lower edge beveled, as indicated at 33, to correspond therewith whereby the section 32 centers itself upon the main body portion of the feeder and is held against lateral movement thereon.

25 In Figure 8 the main body portion 2 of the feeder has its upper edge beveled, as indicated at 34, and the lower end of the section 35 is correspondingly beveled to fit the same and hold the section 35 on the body portion against lateral movement. The upper edge of the section 35 is beveled inwardly, as indicated at 36, so as to receive the lower end of the section 37.

30 In Figure 9 the main body portion 2 of the feeder is beveled, as indicated at 38, in the reverse direction to that in Figures 7 and 8 and the section 39 has its lower end 40 beveled to correspond therewith.

In Figure 10 the main body portion 2 of

the feeder has its upper end beveled, as indicated at 41, the same as shown in Figure 9. The section 42 has its lower end beveled as indicated at 43, to correspond therewith and its upper end beveled, as indicated at 44, to correspond with the bevel of the lower end of the section 45.

35 Figure 11 shows the main body portion 2 of the feeder having an annular recess 46 forming a stepped upper end and the section 47 provided with an annular projection 48 entering the recess. The upper end of the section 47, is provided with an annular recess 49 receiving the projection 50 of the section 51 whereby the sections are interlocked upon the body portion of the feeder or upon each other in their proper position with the inner walls flush with each other.

40 Figure 12 shows the upper end of the main body portion 2 of the feeder provided with an off-set annular flange 52 forming the annular seat 53 adapted to receive the lower end of the section 54 with their inner walls flush. The upper end of the section 54 is provided with an off-set annular flange 55 forming a recess for the section 56 whereby any desired number of sections constructed exactly alike may be placed one upon the other.

45 In Figure 13 the main body portion 2 of the feeder is provided with a semi-circular annular groove 57 in its upper edge adapted to receive the correspondingly shaped lower edge 58 of the section 59. The upper end of the section 59 is provided with an annular recess 60 for receiving the section 61.

50 In Figure 14, instead of having the upper edge of the main body portion 2 of the feeder provided with an annular recess, it is provided with a semicircular curved face 62 adapted to receive a correspondingly shaped groove 63 in the lower end of the section 64. The upper edge of the section 64 is provided with a semicircular face 65 adapted to enter the groove of the section 66.

55 In Figure 15 the projections 67 are constructed exactly like those shown in Figure 2 of the drawings but instead of having two projections on opposite sides, two sides are provided with projections, while the two opposite sides are provided with correspondingly shaped recesses 68. The section 69 is likewise provided with correspondingly shaped recesses 70 and projections 71.

60 Figure 16 shows the upper end of the body portion of the feeder perfectly flat and the section 72 having its lower edge perfectly flat and resting thereon and the same held against lateral movement by a band 73 which may be of any desired form, such as shown in one of our prior patents.

65 From the foregoing description it will be seen that applicants have produced a feeder which can be readily extended to form a longer or shorter feeder to increase the

length of the ingot and at the same time so construct the sections that they are interchangeable.

Having thus described our invention, what we claim is:—

1. A feeder for ingot molds, comprising a series of horizontal sections, and means for holding said sections together.

2. A feeder for ingot molds, comprising a series of horizontal sections provided with interlocking means for holding said sections together.

3. A feeder for ingot molds, comprising a body portion, of a series of horizontal sections adapted to fit upon the body portion, and means for holding said sections together.

4. A feeder for ingot molds, comprising a body portion, of a series of horizontal sections provided with interlocking means for holding the sections on the body portion.

5. A feeder for ingot molds, comprising a body portion, of a series of horizontal sections provided with interlocking means for locking the sections on the body portion and on each other.

6. A feeder for ingot molds, comprising a body portion adapted to be supported in the mold, of horizontal sections provided with means for interlocking with the body portion and with each other.

7. A feeder for ingot molds, comprising a body portion, a series of horizontal sections adapted to rest on the body portion

and upon each other, and means for holding the sections together and to the body portion.

8. A feeder for ingot molds, comprising a body portion, a series of horizontal sections adapted to be stacked one upon the other and having interlocking means for holding the lower section to the body portion and the other sections to each other.

9. A feeder for ingot molds, comprising a body portion, of a series of horizontal sections adapted to fit the body portion, and means for holding said sections together and holding the sections on the body portion.

10. A feeder for ingot molds, comprising a body portion, of a series of horizontal sections provided with means for holding the sections on the body portion.

11. A feeder for ingot molds, comprising a body portion, of a series of sections provided with interlocking means for interlocking with each other and with the body portion.

12. A feeder for ingot molds, comprising a body portion adapted to be supported in the mold, of horizontal sections provided with means for holding it on the body portion and holding said sections on each other.

In testimony whereof we affix our signatures.

BLOOMFIELD H. HOWARD.
ERNEST J. TURNER.
